UNITED STATES PATENT OFFICE.

VINCENT LINK, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

THROTTLE AND SPARK GOVERNOR.

1,108,198.

Specification of Letters Patent. Patented Aug. 25, 1914.

Application filed June 24, 1909. Serial No. 504,168.

To all whom it may concern:

Be it known that I, VINCENT LINK, a citizen of the United States, and resident of Detroit, in the county of Wayne and State 5 of Michigan, have invented certain new and useful Improvements in Throttle and Spark Governors, of which the following is a specification.

This invention relates to hydro-carbon 10 engines and in particular to a governor which controls the speed thereof and also controls the ignition system.

In hydro-carbon engines it is desirable that the spark be advanced as the engine 15 speeds up, and at high speed the ignition must occur before the piston starts on the power stroke. It is therefore desirable to connect the igniter with the governor of the engine so that when the speed rises the 20 spark will be automatically advanced. In engines of the above type, especially when used for driving motor vehicles, as now constructed, the governor or its connections are exposed. The result is that it may easily be 25 tampered with. This is undesirable where the driver of the vehicle is inexperienced and perhaps irresponsible.

The objects of this invention are therefore to provide a governor which will, by a 30 simultaneous movement, advance the spark and control the speed of the engine by throttling or otherwise, to house the governor and its connections, and to arrange the mechanism so that it may not be tampered with 35 without breaking a seal and disconnecting the mechanism or both.

This invention therefore provides means for obtaining the above results. The governor shaft has mounted upon it a suitable 40 centrifugal device which rotates therewith. A sleeve is mounted upon this shaft, and directly connected to arms extending from the centrifugal device. The lower end of the 45 sleeve is connected by means of an arm to the shaft which supports the mixture throttle valve. The commutator shaft is located in alignment with the governor shaft and slidably connected with the sleeve so as to turn therewith. As the engine speeds up, the 50 centrifugal device will simultaneously move the sleeve axially and angularly on the governor shaft, thereby simultaneously throttling the mixture and advancing the spark by advancing the commutator shaft with respect to the governor shaft.

The mixture pipe is preferably located adjacent the governor, and the governor and its connections are housed and protected by a cover which may be sealed in place by a suitable seal band or wire. The commutator 60 shaft is mounted for rotation in the cover plate and is removable therewith, so that when the cover is removed the commutator is disconnected and the motor rendered inoperative. The arm which connects the governor to the throttle shaft is preferably so arranged that when the governor is disconnected this arm will close the throttle. It will thus be seen that when the governor is tampered with the entire motor is rendered 65 inoperative, and it will require a skilled workman to connect the parts properly. The entire housing with its parts may be removed from the motor as a unit.

In the drawings: Figure 1 is a longitudinal sectional view through the governor and commutator shafts on the line 1—1, Fig. 3; Fig. 2 is a plan view of the commutator with its cover removed; Fig. 3 is a section on the line 3—3 Fig. 1; Fig. 4 is a section on the line 4—4 Fig. 1; Fig. 5 is a section on the line 5—5 Fig. 1; Fig. 6 is a detail view of the governor in elevation; Fig. 7 is a detail plan view of the governor with the commutator shaft disconnected; Fig. 8 is a detail 75 of the sleeve and commutator shaft showing the slideable connections.

Referring to the drawings, 20 represents a portion of the crank case. 21 one of the cylinders bolted thereto, as shown at 22, 23 90 the cam shaft, which is driven from the crank shaft by the usual two-to-one gears, 24 represents a portion of the carburetor, and 25 the intake pipe, the intake pipe being connected by suitable connections to the cylinders. In the intake pipe are mounted a pair of butterfly throttle valves 27, 28, the throttle valve 27 being manually controlled from the steering wheel, while the valve 28 95 is automatically controlled by the governor 29 in a manner hereinafter to be described. From the above arrangement it will be seen that the mixture may be controlled manually from the steering wheel, and this control is independent of the operation of the governor controlled valve 28. This valve 28 being connected to the governor is out of the operator's control, and it is the purpose of this invention to suitably house the governor so 100 that this throttle valve cannot be tampered 105 110

with and therefore will absolutely control the maximum speed of the engine.

Upon the governor shaft 30 is mounted a bevel-gear 31, which meshes with the bevel-gear 32 mounted upon the cam shaft 23. Rigidly secured to the shaft 30 are a pair of radial arms 33, upon which are pivotally mounted the governor links 34 provided with the usual balls 35. A sleeve 36 is loosely mounted upon the shaft 30 and provided with a pair of annular flanges 37, which receive a shoe 38 pivotally connected to an arm 39, secured to the operating shaft 40 for the throttle valve 28. The sleeve, as shown in detail in Fig. 8, is provided with a pair of bearing lugs or trunnions 41, upon which are slidably and pivotally mounted the blocks 42, connecting the trunnions with the arms 43 secured to the governor links 34. By means of the above arrangement the governor links will simultaneously move the sleeve 36 axially and angularly on the shaft 30.

The shaft 30 is provided with a nib 44, and axially arranged with respect to the shaft 30 is the commutator shaft 45, which is separated from shaft 30 by means of a sleeve 46, the arrangement being such that shaft 45 may move angularly with respect to the shaft 30. Suitably mounted within a casing is a commutator 47 provided with segments 48 mounted in a ring 45 of insulating material, preferably fiber. Upon the shaft 49 is mounted a rotating arm 50 carrying a contact roller 51, which is constructed to successively contact with the commutator segments 48. The segments 48 are connected by means of a metal strip 52 which forms one of the terminals of the circuit, the other terminal being grounded on the motor frame. The lower end of the commutator shaft is provided with feet 53 which slide between standards 54 upon the sleeve 36, the arrangement being such that sleeve 36 may move axially with respect to shaft 45 and still be connected with it so as to rotate it.

Upon the shaft 30 is mounted a governor spring 55, bearing against the lower flange 37 on the sleeve 36 and against a roller thrust bearing 56. From the above arrangement it will be seen that the connections between the governor links upon the shaft 30, the sleeve 36, and the commutator shaft 45, will rotate the commutator shaft in unison with the governor shaft. When, however, the motor speeds up, the sleeve 36 is moved angularly with respect to the shaft 30, and therefore advances the shaft 45 with respect to the shaft 30, and thus advances the spark.

It will be noted that the intake pipe 25 is located adjacent the governor. The governor is housed by a suitable housing 57, which preferably is integral with the intake

pipe. This housing is provided with a tubular portion 58, and the crank case 20 is provided with an opening 59 through which the bevel-gear 31 may be inserted into engagement with the bevel-gear 32. The tubular portion 58 is provided with a flange 60, whereby the housing may be secured to the crank case 20 by bolts, as shown in Fig. 1. A suitable bearing sleeve 61 is provided for the governor shaft 30.

The housing 57 is closed by a cover 62 provided with an extension 62'. A tube 63 connects this extension with an extension 63' on the commutator casing 64. This tube 63 forms a casing for the commutator shaft and is provided with bearing sleeves 65. The cover 62 is secured to the housing 57 by means of bolts 66, provided with eyes or rings 67 for receiving a seal band or wire 68, the ends of which may be sealed together by a seal or lock 69. The bevel-gear 31 projects from the housing 57, and the opening 59 is of larger diameter than this bevel-gear so that it may be inserted into position in mesh with bevel-gear 32. The housing 57 which supports and incloses all of the working parts may be removed as a unit.

From the above it will be seen that the governor absolutely controls the throttle 28 and simultaneously controls the position of the spark, the entire mechanism being housed so that it cannot be tampered with without detection. In order to tamper with the governor it is necessary that the seal be broken and the cover plate 62 removed. Since this cover plate supports the commutator shaft, the commutator will be disconnected and therefore the engine rendered inoperative. If the governor is disconnected from its throttle valve the arm 39, weighted by the shoe 38, will automatically operate to close the throttle valve, thus providing an additional means for rendering the motor inoperative. Even if this throttle valve arm 39 be tied down there is always the possibility of making an inaccurate connection between the sleeve 36 and the commutator shaft 45. It will thus be seen that even if this governor is tampered with it requires a skilled workman to again adjust the parts so that the motor will be operative.

The above arrangement of providing a governor which cannot be tampered with, and especially a governor which is inclosed in a sealed housing, is advantageous where inexperienced and irresponsible operators are employed for operating the engine, when used in connection with a motor vehicle, and also where the municipal laws require that vehicles operate below a given speed limit.

It is obvious that various changes may be made in the details of construction without departing from the spirit of this invention.

Therefore it is to be understood that this invention is not to be limited to the specific constructions shown.

What I claim is.

5. 1. In a governor, in combination, a rotating shaft having a sleeve mounted thereon, a centrifugal member mounted to rotate with one of said members and move in a plane extending axially of said shaft, and a connection between the centrifugal member and the other member constructed to directly move it angularly and axially.
10. 2. In a governor, in combination, a governor shaft, a centrifugal member mounted thereon to rotate therewith and move in a plane extending axially of said shaft, a sleeve on said shaft, and connections between the centrifugal member and the sleeve constructed to directly move the sleeve angularly and axially on the shaft.
15. 3. In a governor, in combination, a governor shaft, a centrifugal member mounted thereon to rotate therewith and move in a plane extending axially of said shaft, a sleeve on said shaft, and an arm on said centrifugal member connected to the sleeve so as to directly move it angularly and longitudinally on the shaft.
20. 4. In a governor, in combination, a governor shaft, centrifugal members mounted thereon to rotate therewith and provided with rigid arms, a sleeve on said shaft provided with radial bearing lugs, and blocks connecting the arms and the lugs so as to simultaneously move the sleeve angularly and axially.
25. 5. In a governor, in combination, a governor shaft, centrifugal members mounted thereon to rotate therewith and swinging about pivots at right angles to the shaft and provided with rigid arms, a sleeve on said shaft provided with radial bearing lugs, and blocks connecting the arms and the lugs so as to simultaneously move the sleeve angularly and axially.
30. 6. The combination with two aligned shafts, a sleeve having a purely axial sliding connection with one of said shafts and a centrifugal governor mounted on the other shaft, of connections between said governor and the sleeve constructed to directly move the sleeve angularly and axially relative to the governor shaft.
35. 7. In a governor, in combination, a governor shaft, a sleeve mounted thereon, a shaft abutting the governor shaft and slidably connected with the sleeve so as to turn therewith, a centrifugal member mounted to move with the governor shaft, and a connection between the centrifugal member and the sleeve constructed to move it and the shaft angularly and axially with respect to the governor shaft.
40. 8. In a hydrocarbon motor, in combination, a throttle having an operating shaft,
45. a commutator shaft, a governor shaft axially lined with the commutator shaft, a sleeve on the governor shaft connected to rotate therewith and slidably connected with the commutator shaft so as to rotate the same, a centrifugal member mounted on the governor shaft, an arm on the throttle shaft directly connected to the sleeve, and connections between the centrifugal member and the sleeve constructed to move it angularly, to advance the commutator shaft relatively to the governor shaft, and longitudinally to operate the throttle.
50. 9. In a hydrocarbon motor, the combination with the throttle valve thereof and a governor operated by the motor, of means for connecting the governor with the throttle valve, and means whereby the throttle valve is automatically closed upon disconnecting the governor.
55. 10. In a hydrocarbon motor, the combination with the intake pipe and the throttle valve therein, of a governor driven by the motor, a housing for said governor contiguous to said intake pipe, and means for operatively connecting the governor with the throttle valve, said means being entirely enclosed in said housing.
60. 11. In a hydrocarbon motor, the combination with the intake pipe and the throttle valve therein, of a governor driven by the motor, a housing for said governor contiguous to said intake pipe, means for operatively connecting the governor with the throttle valve, said means being entirely enclosed in said housing and intake pipe, and means whereby the throttle valve will be automatically closed upon disconnecting the governor therefrom.
65. 12. In a hydrocarbon motor, the combination with the throttle and spark control mechanisms, of a governor driven by the motor, a housing for said governor, a removable cover for said housing, means for connecting said governor with said throttle and spark control mechanisms, and means whereby the removal of said cover renders the motor inoperative.
70. 13. In a hydrocarbon motor, the combination with the governor driven by the motor and a housing for said governor, of a commutator, the operating shaft of said commutator being detachably connected with the operating shaft of said governor, a cover for said governor housing, and means whereby the commutator is disconnected from the governor shaft when said cover is removed.
75. 14. In a hydrocarbon motor, in combination, a governor driven by the motor, an intake pipe having a throttle therein, connections between the governor and the throttle, and a housing for the governor and connections integral with the intake pipe.
80. 15. In a hydrocarbon motor, in combination,

nation, a governor driven by the motor, an intake pipe having a throttle therein, connections between the governor and the throttle, a housing for the governor and connections integral with the intake pipe, a removable cover for the housing, and sealing means therefor.

16. In a hydrocarbon motor, in combination, a governor driven by the motor, an intake pipe having a throttle therein, an operating shaft for the throttle, an arm on the shaft connected with the governor and constructed when disconnected from the governor to close the throttle, and a housing for the governor and its connections.

17. In a hydrocarbon motor, in combination, a governor shaft driven by the motor, a governor mounted thereon, a housing for the governor, a cover for the housing, and a commutator shaft mounted in the cover and detachably connected to the governor shaft so as to be removed with the cover.

18. In a hydrocarbon motor, the combination with a governor, its shaft, and connections, of a housing inclosing and supporting all of said parts and an intake pipe secured to said housing, said housing and intake pipe being constructed to be detachably secured to the frame so as to be removed as a unit.

19. In a hydrocarbon motor, the combination with a governor, its shaft, and connections, of a housing inclosing and supporting all of said parts, an intake pipe in-

tegral with the housing, said housing and intake pipe being constructed to be detachably secured to the frame so as to be removed therefrom as a unit.

20. In a hydrocarbon motor, the combination with a governor, its shaft, and connections, of a housing inclosing and supporting all of said parts, a gear on the governor shaft outside the housing, said housing being constructed to be detachably secured to the frame so as to locate the gear in mesh with the driving gear on the frame and so as to be removed as a unit.

21. In a governor, the combination with driving and driven shafts, of a member connecting said shafts and having a longitudinal sliding engagement with one shaft, and an engagement with the other shaft permitting both longitudinal and angular movements thereon, and governor mechanism adapted to move said member longitudinally and angularly.

22. In a governor, the combination with driving and driven shafts, of a sleeve having a splined connection with one shaft and a connection with the other shaft permitting both axial and angular movement thereon, and governor mechanism adapted to move said sleeve axially and angularly.

In testimony whereof I affix my signature 65 in presence of two witnesses:

VINCENT LINK.
